US0D1042130S

(12) **United States Design Patent** (10) **Patent No.:** **US D1,042,130 S**
Ramsuer (45) **Date of Patent:** **** Sep. 17, 2024**

(54) **TRIGGER SPRAYER NOZZLE**(71) Applicant: **Silgan Dispensing Systems Corporation**, Grandview, MO (US)(72) Inventor: **Brandon Ramsuer**, Richmond, VA (US)(73) Assignee: **Silgan Dispensing Systems Corporation**, Grandview, MO (US)(***) Term: **15 Years**(21) Appl. No.: **29/914,176**(22) Filed: **Oct. 13, 2023****Related U.S. Application Data**

(62) Division of application No. 29/758,645, filed on Nov. 17, 2020, now Pat. No. Des. 1,005,106.

(51) **LOC (14) Cl.** ..... **09-07**(52) **U.S. Cl.** **D9/448**

CLAIM

The ornamental design for a trigger sprayer nozzle, as shown and described.

DESCRIPTION

FIG. 1 is a perspective view of a trigger sprayer nozzle in accordance with the present design;
FIG. 2 is a front view thereof;
FIG. 3 is a rear view thereof;
FIG. 4 is a right side view thereof;
FIG. 5 is a left side view thereof;
FIG. 6 is a top view thereof;
FIG. 7 is a bottom view thereof; and,
FIG. 8 is another perspective view thereof, shown in an exemplary environment of use.

The broken lines are shown for the purpose of illustrating both parts of the article as well as environmental subject matter. None of the broken lines form part of the claimed design.

1 Claim, 6 Drawing Sheets
